(57) **CLAIM**

The ornamental design for wireless stethoscope, as shown and described.

DESCRIPTION

FIG. 1 is a front perspective view of a wireless stethoscope in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the wireless stethoscope connected to a connector depicted in broken lines, and the broken lines showing of the connector are for purposes of showing environment associated with the wireless stethoscope in condition of use and form no part of the claimed design.

Broken lines, other than those described in the FIG. 8, show portions of the wireless stethoscope that form no part of the claimed design.
